Primary Examiner—Caron D. Veynar

Assistant Examiner—Vy Nguyen

(74) **Attorney, Agent, or Firm**—Ronald A. Sandler; Jones Day

(57) **CLAIM**

The ornamental design for a wire frame for chair, as shown and described.

DESCRIPTION

FIG. 1 is a front isometric view of the wire frame for chair.

FIG. 2 is a rear isometric view thereof.

FIG. 3 is a front view thereof.

FIG. 4 is a rear elevation view thereof.

FIG. 5 is a right side elevation view thereof.

FIG. 6 is a left side elevation view thereof.

FIG. 7 is a top plan view thereof; and,

FIG. 8 is a bottom plan view thereof.

The broken line showing of the chair seat, back and legs is for illustrative purposes only and forms no part of the claimed design.

1 Claim, 5 Drawing Sheets
